CYLINDRICAL GRINDING MACHINE

Herbert A. Silven, Worcester, Mass., assignor to
 Norton Company, Worcester, Mass., a corpora-
 tion of Massachusetts

Application June 11, 1945, Serial No. 598,799

11 Claims. (Cl. 51—95)

1

This invention relates to grinding machines, and more particularly to a hydraulically operated cylindrical grinding machine.

One object of the invention is to provide a simple and thoroughly practical cylindrical grinding machine. Another object of the invention is to provide a hydraulically operated cylindrical grinding machine which is arranged so that either a hand or an automatic cycle of operation may be readily obtained. Another object of the invention is to provide a hydraulically operated cylindrical grinding machine in which a traverse grinding operation may be obtained, in which the grinding wheel is automatically fed into the work at the ends of the reciprocatory stroke of the work piece. Another object of the invention is to provide a grinding machine in which the hydraulically operated table reciprocating mechanism and the hydraulically operated grinding wheel feeding mechanism may be independently and manually controlled or in which the infeeding movement of the grinding wheel may be automatically actuated at the ends of the work table stroke.

Another object of the invention is to provide a hydraulically operated cylindrical grinding machine in which a selector valve is provided by means of which the machine may be readily set up for either a traverse grinding operation with an automatic infeed at the ends of the work table stroke or the machine may be set up for an automatic cycle of operation in which a plunge-cut feeding movement of the grinding wheel is obtained and automatic rapid return.

Another object of the invention is to provide a feeding mechanism in which a vane-type motor is provided to rotate the feed screw either continuously for a plunge-cut grinding operation or intermittently at the ends of the table stroke or a traverse grinding operation. Another object of the invention is to provide a control mechanism for said vane-type motor which is arranged to allow the motor vane to rotate at a comparatively rapid rate during its initial movement on either a plunge-cut or a traverse grinding operation to take up the backlash in the feeding mechanism parts before the grinding wheel moves into grinding engagement with the work piece. A further object of the invention is to provide a shuttle type valve, the speed of movement of which may be regulated so as to meter a predetermined amount of fluid from the vane feeding motor to obtain an initial rapid movement of the motor vane so as to take up the backlash between the feed screw and nut before the

2

grinding operation is started. Other parts will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

10 One embodiment of the invention has been illustrated in the drawings, in which:

Fig. 1 is a front elevation of the improved hydraulically operated cylindrical grinding machine;

15 Fig. 2 is a diagrammatic illustration of the hydraulic control mechanisms and a simplified electric diagram of the work driving mechanism; Fig. 3 is a fragmentary front elevation, on an enlarged scale, of the wheel feeding mechanism as shown in Fig. 1, having the manually operable feed wheel removed;

20 Fig. 4 is a fragmentary sectional view, taken approximately on the line 4—4 of Fig. 3;

Fig. 5 is a vertical sectional view, on an enlarged scale, taken approximately on the line 5—5 of Fig. 3, through the hydraulically actuated continuous infeeding mechanism;

25 Fig. 6 is a fragmentary sectional view, on an enlarged scale, through the latch stud for holding the power feed mechanism in an operative position for an automatic infeeding movement of the grinding wheel;

30 Fig. 7 is a similar fragmentary sectional view, on an enlarged scale, showing the latch pin in a position for a hand feeding operation;

35 Fig. 8 is a fragmentary sectional view, on an enlarged scale, taken approximately on the line 8—8 of Fig. 4, showing the stud locating device;

40 Fig. 9 is a vertical sectional view, on an enlarged scale, through the selector valve; and

Fig. 10 is a fragmentary view, taken approximately on the line 10—10 of Fig. 9, showing the stop device for limiting the rotary movement of the selector valve.

45 An improved hydraulically operated cylindrical grinding machine has been illustrated in the drawings comprising a base 10 which serves to support a longitudinally reciprocable work supporting table 11. The table 11 is arranged to be traversed or reciprocated longitudinally on a flat way 12 and a V-way 13 formed on the upper surface of the base 10. The table 11 may be traversed longitudinally by a manually operable hand wheel 14 through a manually operable traverse mechanism to be hereinafter described.

Table reciprocation

A fluid pressure mechanism is provided for reciprocating the table 11 longitudinally comprising a cylinder 15 which is fixed relative to the base 10. The cylinder 15 contains a slidably mounted piston 16 which is fixedly connected to a double end piston rod 17. The opposite ends of the piston rod 17 are connected by depending brackets 18 and 19 fixedly mounted on the under side of the table 11 at its opposite ends.

A table reversing or control valve 20 is provided for controlling the admission to and exhaust of fluid from the cylinder 15. When fluid under pressure is passed through a pipe 21 and a passage 22 into a cylinder chamber 23, it will cause the piston 16 and table 11 to move toward the right (Fig. 1). During the movement of the piston 16 toward the right, fluid within a cylinder chamber 24 will exhaust through a passage 25 and through a pipe 26 to the control valve 20.

The table 11 serves as a support for a rotatable work piece 27. The work piece 27 is supported on a headstock center 28 and a footstock center 29 which are in turn supported by a headstock 30 and a footstock 31, respectively. The headstock 30 is preferably a motor driven headstock comprising an electric motor 32 which is provided with a driving pulley 33 (Fig. 2) which is connected by multiple V-belts 34 with a pulley 35 to drive the work piece 27 during a grinding operation.

Grinding wheel feed

A transversely movable wheel slide 38 is arranged to move transversely relative to the base 10 on a V-way 39 and a flat way 40 (Fig. 1). The wheel slide 38 is provided with a rotatable wheel spindle which supports a rotatable grinding wheel 42 at its left-hand end (Fig. 1). The spindle and grinding wheel 42 are preferably positively driven by a suitable driving mechanism such as, for example, an electric motor 43 which is mounted on the upper surface of the wheel slide 38. The motor 43 is provided with an armature shaft 44 which supports a multiple V-groove pulley 45. The pulley 45 is connected by multiple V-belts 46 with a multi-V-groove pulley 47 which is mounted on the right-hand end of the wheel spindle.

A nut and screw feed mechanism is provided for feeding the wheel slide 38 transversely relative to the base 10. This mechanism may comprise a rotatable feed screw 50 which meshes with a depending half nut 51 fastened to the under side of the wheel slide 38. A reduced end portion 52 of the feed screw 50 is slidably keyed within a rotatable sleeve 53. The sleeve 53 is journaled in anti-friction bearings 54 and 55 which are in turn fixed relative to the base 10. The right-hand end of the feed screw 50 is journaled in a suitable bearing (not shown) in a slidably mounted sleeve 56 which is slidably keyed within a portion of the base 10.

In order to move the wheel slide 38 rapidly to and from a grinding position, a hydraulically operated mechanism is provided comprising a hydraulic cylinder 57 which contains a slidably mounted piston 58. The piston 58 is connected to a double end piston rod 59, the left-hand end of which is fastened to the slidably mounted sleeve 56. As illustrated in Fig. 2, the piston rod 59 is arranged in axial alignment with the axis of the feed screw 50.

A control valve 60 is provided for controlling the admission to and exhaust of fluid from the cylinder 57. When fluid under pressure is admitted

through a pipe 61 into a cylinder chamber 62, it will cause the piston 58, the feed screw 60, and the wheel slide 38 to move to an operative position relative to the work piece 27 to be ground. During this movement, fluid within a cylinder chamber 63 exhausts through a pipe 64. Similarly, when fluid under pressure is admitted to the cylinder chamber 63, the piston 58, the wheel slide 38 and the grinding wheel 42 will be moved to a rearward or inoperative position.

A manually operable feed wheel 70 is provided for manually rotating the feed screw 50 to impart a transverse feeding movement to the wheel slide 38. The feed wheel 70 is rotatably supported on a rotatable shaft 72 which is journaled in bearings (not shown) in the base 10. The feed wheel 70 is provided with the old and well known micrometer adjusting mechanism 75 having a feed gear 73 fixedly mounted on the shaft 72, which is substantially the same as that shown in the expired U. S. Patent No. 762,838 to C. H. Norton dated June 14, 1904, to which reference may be had for details of disclosure not contained herein. A pinion 76 (Fig. 1) is formed integral with the shaft 72 and is mounted to rotate with the hand wheel 70. The pinion 76 meshes with a gear 77 mounted on a rotatable shaft 78. The gear 77 meshes with a gear 79 which is formed integral with the sleeve 53. It will be readily apparent from the foregoing disclosure that a rotary motion of the hand wheel 70 will be transmitted through the gear mechanism above described to rotate the feed screw 50 so as to cause a transverse feeding movement of the wheel slide 38.

35 A power operated feeding mechanism is provided which is arranged to rotate the feed screw 50 either intermittently at the ends of the table stroke for a traverse grinding operation or continuously for a plunge-cut grinding operation. 40 This mechanism preferably comprises a rotary vane type motor 85 having a rotatable rotor shaft 86. A rotor 87 is formed integral with the shaft 86 and serves as a support for a single vane 88 (Fig. 2). A fixed plate 89 within the motor 85 45 serves to limit the rotary motion of the vane 88. When fluid is admitted through a passage 90 into a motor chamber 91, the rotor 87 and vane 88 will be moved in a counterclockwise direction (Fig. 2) to cause an infeeding movement of the grinding 50 wheel 42. During this movement, fluid within a motor chamber 92 will exhaust through a passage 93.

55 A control valve 95 is provided for controlling the admission to and exhaust of fluid from the motor 85. The valve 95 comprises a valve stem 96 having a plurality of valve pistons formed integrally therewith so as to provide a plurality of valve chambers 97, 98, 99, 100 and 101. In the position of the parts illustrated in Fig. 2, fluid under pressure enters the valve chamber 99 and the passage 90 and passes into the motor chamber 91 to start a counterclockwise rotation of the vane 88 to produce an infeeding movement of the grinding wheel 42. The valve 95 is preferably hydraulically 60 actuated in timed relation with the other mechanisms of the machine. A pipe 103 is connected with the valve chamber 101 and serves to convey fluid under pressure to move the valve stem 96 to its extreme left-hand end position (Fig. 2). 70 Similarly, a pipe 104 is connected at the other end of the valve 95 to admit fluid to or exhaust fluid from the valve chamber 97 formed at the left-hand end of the valve 95. When fluid under pressure is passed through the pipe 103 into the chamber 75 101, the valve stem 96 will be moved toward

the left (Fig. 2) to reverse the direction of movement of the vane 88; exhausting through a pipe 102, so as to return the grinding wheel 42 to its starting position.

The rotor shaft 86 of the motor 85 is provided at its outer end with a gear 110 which is keyed thereto. The gear 110 meshes with a gear 111 which is mounted on a shaft 112. A gear 113 is formed integral with the gear 111. The stud or shaft 112 is fixedly mounted within a casing 114. The casing 114 is preferably fixedly mounted to a flange 115 (Fig. 5) which is formed integral with a rotatable sleeve 116. The sleeve 116 is journaled in an aperture 117 which is formed integral with the vane motor 85. The casing 114 is arranged so that the gear 113 may be moved in a clockwise direction into either the position 113a or 113b so that a stop abutment 118 which is integral with the casing 114 may be swung into an operative position in the path of a stop abutment 119 carried by the manually operable feed wheel 70. The stop abutment 119 serves as a positive stop to limit the rotary infeeding movement of the hand wheel 70.

The casing 114 which supports the feed gearing above described may be moved to an operative position, in which position a slidably mounted latch stud 120 having a reduced irregularly shaped portion or pin 121 may slide into engagement with a locating surface 122 on a block 123 fixed relative to the base 10 of the machine. When the pin 121 is in the position 121a (Fig. 6), it serves to locate the casing 114 and the gear 113 in position 113a. When it is desired to move the gear 113 from position 113a into position 113b, the latch stud 120 may be rotated counterclockwise to position the pin 121 in position 121b as shown in Fig. 7. It will be readily apparent from the foregoing disclosure that, depending upon the position of the pin 121, the gear 113 may be located either in position 113a or 113b (Fig. 3).

In order to facilitate readily positioning and holding the latch stud 120 with the pin 121 either in position 121a or 121b, a pair of diametrically opposed elongated V-shaped notches 124 are provided on the latch stud 120 (Figs. 4 and 8). A spring-pressed ball 125 is supported by the frame 114 and is arranged to frictionally engage either one or the other of notches 124 on the latch stud 120. A handle knob 126 is provided on the stud 120 to facilitate positioning of the pin 121 (Figs. 3 and 5) so that the casing 114 may be rocked to position the driving gear 113 either in position 113b for a hand feeding operation, or in position 113a for a power feeding of the grinding wheel 42. It will be readily apparent from the foregoing disclosure that a rotary motion of the vane 88 of the motor 85 will be transmitted through the gear mechanism above described to rotate the shaft 72 and the feed screw 50 and thus impart an infeeding movement to the grinding wheel 42.

In order to facilitate movement of the feed gear into an operative position, a manually operable lever 127 is pivotally mounted on a pin 128 (Figs. 3, 4 and 5) which is carried by the housing 114. The lower end of the lever 127 is provided with an aperture 129 which surrounds the outwardly extending grooved portion of the latch stud 120. The lever 127 may be swung in a clockwise direction (Figs. 1 and 3) to throw the gear 113 into an operative position. When it is desired to disconnect the power feed gear 113 from an operative position, the lever 127 may be swung in a counterclockwise direction (Fig. 4) to withdraw the stud 120 and the pin 121, that is, to move it to

ward the right (Fig. 4) to withdraw the pin 121 out of engagement with the locating surface 122, and the released tension of a spring 130 will shift the housing 114 to an inoperative position with the gear 113 in the full line position as indicated in Fig. 3. The spring 130 is connected between a stud 131 which is fixed relative to the base 10 and a stud 132 which is fixed relative to the gear casing 114 (Figs. 3 and 4). A pin 133 (Figs. 3 and 4) which is fixed relative to the base 10 limits the movement of the housing 114 towards an inoperative position. The spring 130 serves normally to maintain the housing 114 in engagement with the pin 133.

Wheel feed-control valve

The feed control valve 60 is preferably a piston type valve comprising a valve stem 135 having formed integrally therewith valve pistons 136, 137 and 138. An actuating knob 139 is fixedly mounted on the outer end of the valve stem 135. The valve stem 135 is arranged so that, if desired, it may be locked in either a right-hand or a left-hand end position (Fig. 2) by means of a pin 140. A pair of transverse grooves 141 and 142 are provided in the valve stem 135. The slots 141 and 142 are connected by a longitudinally extending slot 143. When the slot 143 is aligned with the pin 140, the valve stem 135 may be moved longitudinally as desired. If it is desired to latch the valve stem 135 in either a right-hand or a left-hand end position (Fig. 2), the valve stem 135 is moved into the desired position, after which the knob 139 may be rotated so that the pin 140 engages either the transverse groove 141 or the transverse groove 142 to lock the valve stem 135 against endwise movement so that the wheel slide 38 will be maintained either in a forward operative position or in a rearward inoperative position.

In the position of the valve 60 (Fig. 2), fluid under pressure passing through a pipe 144 enters a valve chamber 145 located between the valve pistons 136 and 137 and passes out through the pipe 64 into the cylinder chamber 63 to move the piston 58 and the wheel slide 38 to a rearward or inoperative position. During this movement of the piston 58, fluid within the cylinder chamber 62 exhausts through the pipe 61 into a valve chamber 146 located between the valve pistons 137 and 138 and passes out through a pipe 147 into a reservoir 148.

Manual table traverse

A manually operable traversing mechanism is provided for adjusting the table 11 longitudinally relative to the base 10. This mechanism is actuated by the manually operable traverse wheel 14 which is rotatably mounted on a stud 150. A gear 151 is fixedly mounted to rotate with the hand wheel 14. The gear 151 meshes with a gear 152 which is keyed to a shaft 153. The shaft 153 also supports a gear 154 which meshes with a gear 155. The gear 155 is rotatably supported on a stud 156 and meshes with a rack bar 157 depending from the under side of the work table 11. It will be readily apparent from the foregoing disclosure that a rotary motion of the hand wheel 14 will be transmitted through the gearing above described to traverse the table 11 longitudinally. The direction of movement of the table 11 will be determined by the direction of rotation of the hand wheel 14.

It is desirable to render the hand wheel 14 inoperative so that it will remain stationary dur-

ing the hydraulic traverse or reciprocation of the table 11. The gear 154 is preferably rotatably supported on the shaft 153 and is provided on its right-hand side face (Fig. 2) with clutch teeth 158 which are arranged to be engaged by clutch teeth formed on a slidably mounted clutch member 159. The clutch member 159 is slidably keyed to the shaft 153. In order to disconnect the clutch parts 158-159, a fluid pressure cylinder 160 is provided which contains a slidably mounted piston 161. The piston 161 is fixedly mounted on the right-hand end of the clutch member 159 (Fig. 2). In the position of the mechanism illustrated in Fig. 2, the clutch parts 158-159 are maintained in engagement by means of a plurality of symmetrically arranged compression springs 162, only one of which has been illustrated in Fig. 2. When it is desired to disconnect the hand wheel 14 during hydraulic traverse of the table 11, fluid under pressure is passed through a pipe 163 into the cylinder chamber 164 to move the piston 161 toward the right (Fig. 2) so as to disconnect the clutch parts 158-159, thereby rendering the manually operable hand wheel 14 inoperative.

Automatic control-headstock motor

It is desirable to provide a suitable control mechanism for automatically starting and stopping the headstock driving motor 32 in timed relation with the other mechanism of the machine when an automatic cycle is employed. Power is supplied to the motor 32 from power lines 165. A manually operable switch 166 serves to close the motor circuit to facilitate manual control of the headstock when desired. It is preferable to provide a motor 32 which is of a variable speed type so that the speed of rotation of the work piece 27 may be readily adjusted. As shown diagrammatically in Fig. 2, an adjustable rheostat 167 is provided for regulating the speed of the motor 32. In actual construction, however, an electronic control mechanism is preferably provided such as, for example, that manufactured by General Electric Company and known as the "Thymotrol." A normally open limit switch 168 is provided in the motor circuit to facilitate automatically starting the motor 32 in timed relation with the other mechanisms of the machine during an automatic cycle. A hydraulically operated mechanism is provided for actuating the limit switch 168 comprising a hydraulic cylinder 169 which contains a slidably mounted piston 170. A piston rod 171 is connected at one end with the piston 170 and at the other end engages a roller 172 mounted on an actuating arm 173 of the limit switch 168. A compression spring 174 normally maintains the piston 170 in an uppermost position (Fig. 2) so that the switch 168 is normally open.

When fluid under pressure is passed through a pipe 175 into a cylinder chamber 176 above the piston 170, the piston 170 moves downwardly against the compression of the spring 174 to close the normally open limit switch 168 and thus automatically start the rotation of the headstock motor 32. Similarly, when fluid is permitted to exhaust through the pipe 175, the released compression of the spring 174 will return the piston 170 to its uppermost position to open the limit switch 168 and thereby stop the motor 32.

Table Reverse Valve

The table reversing valve 20 is preferably a piston type valve comprising a shuttle type re-

versing valve member 180 which is provided with a plurality of integrally formed pistons 181, 182, and 183. The reversing valve member 180 is preferably slidably mounted on a valve stem 184. A pair of independent valve members 185 and 186 are fixedly mounted on opposite ends of the valve stem 184 (Fig. 2). A spool-shaped member 187 is fixedly mounted on the right-hand end of the valve stem 184 and is provided with an annular groove 188 which is engaged by a stud 189. The stud 189 is fixedly mounted on a rock arm 190. The rock arm 190 is fixedly mounted on a rock shaft 191 the outer end of which carries a table actuated reversing lever 192. A stud 193 is mounted adjacent to the upper end of the reversing lever 192 and is arranged in the path of movement of a pair of adjustably mounted table dogs 194 and 195. The table dogs 194 and 195 are adjustably supported by means of a longitudinally extending T-shaped slot 196 formed in the front edge of the work supporting table 11.

A motor driven fluid pump 200 is provided for supplying fluid under pressure to the hydraulic system. The pump 200 draws fluid through a pipe 201 from the reservoir 148 and passes fluid under pressure through a pipe 202 to the various mechanisms of the machine. A relief valve 203 is connected in the pipe line 202 to facilitate maintaining the desired operating pressure within the hydraulic system. If pressure builds up beyond the predetermined pressure required, the relief valve 203 opens and by-passes excess fluid under pressure directly to the reservoir 148.

The pipe 202 is connected to supply fluid under pressure to the table reversing valve 20. In the position of the valve 20 (Fig. 2), fluid under pressure from the pipe 202 enters a valve chamber 204 located between the valve pistons 181 and 182 and passes out through a pipe 21 into the cylinder chamber 23 to cause the piston 16 and table 11 to move toward the right (Figs. 1 and 2). During this movement of the table 11, fluid within the cylinder chamber 24 exhausts through the pipe 26 and through a valve chamber 205 located between the valve pistons 182 and 183 and passes out through an exhaust pipe 206.

Start and stop valve

A start and stop valve 210 is provided for controlling the exhaust of fluid from the reversing valve 20. A manually operable actuating knob 209 is mounted on the outer end of a valve stem 211 by means of which the valve 210 may be manually controlled. This valve 210 is a piston type valve comprising the valve stem 211 having formed integrally therewith valve pistons 212, 213, 214, 215, 216 and 217. In the position of the valve 210 (Fig. 2), a by-pass is provided to facilitate a manual traversing movement of the table 11. A pipe 218 and pipe 21 connect the valve chamber 204 in the valve 20 with a valve chamber 219 formed in the start and stop valve 210. A similar pipe 220 connects the chamber 205 of the reversing valve 20 with the chamber 219 of the start and stop valve 210. It will be readily apparent from the foregoing disclosure that when the table 11 is traversed manually by rotation of the traverse hand wheel 14, fluid may readily by-pass from the cylinder chamber 23 through the reversing valve 20, through the by-pass valve chamber 219 in the start and stop valve 210, and into the cylinder chamber 24, thus allowing free manual traverse of the table 11 without the neces-

sity of overcoming the resistance of oil or fluid within the hydraulic system.

The start and stop valve 210 is provided with a V-port 221 which is preferably formed in the valve piston 213 which is arranged so that when the valve stem 211 is moved toward the left (Fig. 2) to start hydraulic operation of the machine, fluid exhausting through the pipe 205 from the reversing valve 20 will pass through the V-port 221 and out through a pipe 222. The pipe 222 is connected to exhaust fluid into the reservoir 148.

Coolant supply

It is desirable to provide a suitable coolant fluid supply for supplying coolant fluid or grinding lubricant to the grinding wheel and work at the point of grinding contact therebetween. In a machine adapted for automatic operation, it is desirable to provide a coolant system whereby the coolant fluid may be automatically started and stopped in timed relation with the grinding operation. As illustrated in Fig. 2 of the drawings, coolant fluid may be supplied through a pipe 230 from a suitable source (not shown), such as a coolant tank in or adjacent to the base of the machine or from a main coolant supply located at a station remote from the grinding machine. Fluid passing through the pipe 230 is controlled by a gate-type valve 231. When the valve 231 is opened, coolant fluid may pass through a pipe 232, through a manually operable valve 241, to a coolant spout 242 which is adjustably supported to convey coolant fluid to the grinding wheel 42 and the work piece 27.

The valve 231 is provided with a valve stem 233 which is preferably actuated automatically by a hydraulically operated mechanism in timed relationship with the other mechanisms of the machine. This hydraulic mechanism may comprise a fluid pressure cylinder 234 mounted on the base 10 (Fig. 1) which contains a slidably mounted piston 235. The piston 235 is connected to one end of a piston rod 236, the other end of which is connected by a stud with the valve stem 233. A compression spring 237 serves normally to hold the piston 235 in the position illustrated in Fig. 2 with the gate valve 231 closed. When it is desired to open the gate valve 231 and thereby start the flow of coolant fluid, fluid under pressure is admitted through a pipe 238 into a cylinder chamber 239 to cause the piston 235 to move toward the right, thus moving the valve stem 233 toward the right to open the valve 231. An adjustable stop screw 240 is provided to limit the movement of the piston 235 toward the right and serves to permit variation in the aperture of the valve 231 so as to allow the desired amount of coolant fluid to pass through the valve 231 into the pipe 232.

Table dwell control valve

It is desirable to provide a suitable dwell control means whereby in a traverse grinding operation the table may be caused to dwell for a predetermined adjustable period at reversal so that the grinding wheel may be fed into the work while the table and work piece are stationary. A dwell control valve 250 is provided which is arranged to control fluid exhausting through either a pipe 251 or a pipe 252. Fluid exhausting through either the pipe 251 or the pipe 252 enters a chamber 253 in the valve 250 and may pass out through a V-port 254 and a pipe 255 which exhausts into the reservoir 148. A manual actuating knob 255 is mounted on the outer end of the valve stem 250 and is located on the front

of the machine base. By a rotary adjustment of the knob 255, the V-port 254 may be adjusted so that the amount of fluid exhausting from either the pipe 251 or 252 may be readily controlled so as to produce the desired dwell at the ends of the table stroke.

Vane motor—Feed control

It is desirable to provide suitable means for regulating the speed of rotation of the vane 88 of the vane motor 85 so that the speed thereof may be readily controlled for either a plunge-cut or a traverse grinding operation. When it is desired to start a feeding cycle, the knob 139 is moved toward the left (Fig. 2), which movement serves to admit fluid under pressure into the valve chamber 97 to shift the valve stem 96 toward the right so that fluid under pressure passing through the pipe 105 will enter the valve chamber 99 and pass through the passage 98 into the motor chamber 91 to cause a counterclockwise movement of the vane 88, thereby producing an infeeding movement of the grinding wheel 42. During this movement, fluid within the motor chamber 92 exhausts through the passage 93, the valve chamber 100, and passes out through a pipe 257 which passes fluid through a chamber in a selector valve 258 (section 258b—Fig. 2) and out through a pipe 259 to a needle type throttle valve 260 which is provided with a manual actuating knob 261. This valve is preferably arranged so that the actuating knob 261 is located on the front of the machine base to facilitate adjustment thereof during a grinding operation. Fluid passing through the throttle valve 260 may pass out through a pipe 262 which exhausts into the reservoir 148. It will be readily apparent from the foregoing disclosure that by controlling the aperture of the valve 260, the speed of counterclockwise rotation of the vane 88 may be readily controlled to produce the desired plunge-cut feeding operation of the grinding wheel 42.

If the machine is set up for a traverse grinding operation, a rotor 263 of the selector valve 258 is rotated 45 degrees in a clockwise direction (Figs. 2 and 10) so that fluid from the vane motor chamber 92 exhausting through the pipe 257 and the selector valve 258b (Fig. 2) passes through a passage 264 in the selector valve rotor 263 and passes out through a pipe 265 and through a needle type throttle valve 266. The needle valve 266 is provided with a manual actuating knob 267 located on the front of the machine base to facilitate adjustment of the valve from the operator's control station.

In a traverse grinding operation, it is desirable that the grinding wheel be fed into the work only during reversal of the table, that is, at the ends of a grinding stroke. It is, therefore, desirable to provide control means for allowing a predetermined amount of exhaust to pass through the needle valve 266 during reversal of the work table movement. The valve 266 is connected by a pipe 268 with a fluid pressure actuated shuttle type valve 269. The valve 269 is provided with a valve piston 270 which is slidably mounted therein. A valve chamber or groove is formed in the valve piston 270 so that when the valve piston 270 moves in either direction the chamber passes across the port at the end of the pipe 268 so as to allow a predetermined exhausting of fluid from the pipe 268 into a pipe 272 which exhausts fluid into the reservoir 148.

In order to provide an infeeding movement of

the wheel slide 38 during reversal of the table 11, a suitable control valve 273 is provided. This valve is preferably a piston type valve comprising a valve stem 274, the right-hand end of which is connected by a stud 275 which is supported on the upper end of the rock arm 190. It will be readily apparent from the foregoing disclosure that each time the reversing lever 192 is actuated to cause a reversal in direction of movement of the work table 11, the rock arm 190 will actuate the valve stem 274. Fluid under pressure from the pump 200 passing through the pipe 202 enters a chamber formed adjacent to the right-hand end of the valve 20 and is arranged to pass through a passage 277 into a valve chamber 278 formed in the valve stem 274. In the position of the valve 273 (Fig. 2), fluid entering the chamber 278 passes out through a pipe 279 and through a needle type throttle valve 280 into a chamber 281 formed at one end of the shuttle type valve 269 to cause the piston 270 to move into its uppermost position (Fig. 2). During this movement of the piston 270, fluid within a similar chamber 281 may exhaust through a needle type throttle valve 283 and a pipe 284 into a chamber 285 formed in the valve stem 274 and pass outwardly through a pipe 286 which returns exhausting fluid to the reservoir 148. Similarly, when the reversing valve 20 is shifted at the other end of the table stroke, the valve stem 274 is shifted toward the right (Fig. 2) so that fluid under pressure passes from the valve chamber 278 through the pipe 284 into the fluid chamber in the valve 269 to cause a reverse movement of the piston 270. By adjustment of the throttle valves 280 and 283, the speed of movement of the valve piston 270 may be readily controlled so that a desired amount of fluid exhausting through the pipe 268 may pass through the valve chamber of the valve piston 270 and out through the pipe 272 into the reservoir 148 so that the vane 88 may rotate through a predetermined arcuate distance during each reversal of the table 11 to impart a predetermined infeeding movement to the grinding wheel 42 at each end of the table stroke.

In an automatic plunge-cut grinding operation, it is desirable to provide a suitable mechanism so that the valve 60 may be manually shifted to initiate a grinding cycle, after which the valve 60 may again be automatically shifted to terminate the grinding operation after the work piece 27 has been ground to a predetermined size. In order to provide free movement of the feed control valve 60 so that it may be readily shifted without bucking fluid under pressure, a fluid operated four-way valve 290 is provided. The valve 290 may be a standard valve, such as that manufactured by Vickers, Inc. As shown in Fig. 2, fluid within an end chamber 291 of the valve 60 may exhaust through a pipe 292, through a valve chamber 293 in the valve 290, and pass outwardly through an exhaust pipe 294 which returns exhausting fluid to the reservoir 148. It will be readily apparent that in the position illustrated in Fig. 2, the valve 60 may be readily moved toward the left without undue effort on the part of the operator, so as to initiate a plunge-cut grinding feed.

A suitable cycle time control valve 300 is provided for controlling the duration of the grinding cycle. This valve is a piston type valve comprising a slidably mounted piston 301. When the feed valve 60 is moved toward the left into a grinding position, fluid under pressure passing

from the valve 60 through the pipe 61 passes through a chamber 302 formed in the rotor 263 of the selector valve 258 (Fig. 2) on section line C—C (Fig. 9) and passes out through a pipe 303 into a valve chamber 304 to cause the piston 301 of the timer valve 300 to move toward the left (Fig. 2). During this movement of the piston 301, fluid exhausts from a chamber 305, out through a pipe 306, through a needle type throttle valve 307, through the pipe 64, into the valve chamber 145, into the valve 60 and passes out through the exhaust pipe 147 into the reservoir 148. It will be readily apparent from the foregoing disclosure that by regulation of the throttle valve 307, the speed of movement of the piston 301 may be readily controlled as desired. After the valve piston 301 has moved to a predetermined position in its movement toward the left, fluid under pressure within the valve chamber 304 may enter an internal circular groove and pass through a pipe 308 which conveys fluid into an end chamber 309 in the valve 290 to shift the valve stem toward the left so that fluid under pressure from the pump 200 passing through the pipe 114 may pass into the valve chamber 293 and through the pipe 292 into the valve chamber 291 in the valve 60 to shift the valve stem 135 toward the right into the position illustrated in Fig. 2. This movement of the valve 60 serves to reverse the flow of fluid to the wheel slide cylinder 57 and also to the vane motor 85 so that the grinding wheel slide 38 and the grinding wheel 42 are moved automatically to a rearward or inoperative position.

The movement of the timer valve piston 301 toward the right is limited by a manually adjustable stop screw 311 which is actuated by means of a manual control knob 312. When fluid under pressure is passed through the pipe 64 to re-set the timer valve 300 and also to return the wheel slide 38 to its rearward position, fluid may pass through the needle valve 307 into the timer valve chamber 305 and may also pass freely through a check valve 313 into the chamber 305 so that the timer valve piston 301 may be returned rapidly to its right-hand or initial position (Fig. 2). Similarly, fluid exhausting through the pipe 308, after the piston 301 covers the port at the end of the pipe 308, may pass around an internal groove 50 formed in the casing of the valve 300 and out through a check valve 314.

In order that the work rotation may be automatically started and the coolant fluid automatically turned on in timed relation with the plunge-cut infeeding operation, fluid under pressure passing through the pipe 61 to the selector valve 258c may pass through a valve chamber 310 formed in the rotor 263 and may pass out through the pipe 175 to convey fluid under pressure to the cylinders 169 and 234, as above described, automatically to start the work rotation and to turn on the supply of coolant fluid.

It is desirable to provide a suitable control mechanism which is operative on both a plunge-cut feed and also a traverse grinding feed so that the vane 88 of vane motor 85 moves initially at a comparatively rapid rate to take up the backlash between the feed screw 50 and the half nut 51. This mechanism serves to take up the backlash in the feed mechanism before the grinding wheel engages the work to be ground. When the grinding wheel moves into grinding engagement with the work piece lever the speed of movement on the vane 88 is reduced to a predetermined grinding feed as governed by the needle valve 260 on a

plunge-cut grinding operation or by the needle valve 266 during a traverse grinding operation. This control mechanism may also be utilized if desired to produce a shoulder grinding feed at a comparatively rapid rate for grinding a shoulder on the work piece after which it may be slowed down to a normal body or grinding feed as governed by the throttle valve 260.

This mechanism may comprise a shuttle type valve 315 having a slidably mounted valve piston 316. The valve piston 316 is provided with a valve chamber which is arranged so that fluid may pass from the pipe 257, through the valve chamber into a pipe 317 during the movement of the valve piston 316 in either direction. The amount of fluid passing through the pipe 317 may be readily controlled by means of an adjustable needle valve 319 so that the exhaust of fluid passing through the shuttle valve 315 may be readily controlled. Fluid exhausting through the needle valve 319 may pass through a pipe 320 which returns exhausting fluid to the reservoir 148. A needle valve 321 is provided in the pipe line 103 to throttle fluid exhausting from a valve chamber 322 formed at the lower end of the shuttle valve 315 so as to control the rate of downward movement of the shuttle valve piston 316. A check valve 323 is connected in the pipe line 103 so that when fluid under pressure is passed through the pipe 103, it may pass rapidly through the check valve 323 into the shuttle valve chamber 322 to cause a rapid upward movement of the shuttle valve piston 316. When fluid under pressure is passed through the pipe 104 into a valve chamber formed at the upper end of the shuttle valve 315 to cause a downward movement of the piston 316, fluid may be exhausted from the lower chamber 322 at a readily controlled rate by manipulation of the needle valve 321 so that a controlled amount of exhaust fluid may be passed from the pipe 257 into the pipe 318. This exhaust of fluid through the pipes 257 and 317 is in addition to the exhaust permitted by the setting of the needle valve 260 so that during the passage of the valve chamber of the shuttle piston 316 by the pipe 257 an increased speed may be obtained in the rotation of the vane 88 of the motor 85 to provide the desired shoulder grinding feed. After the valve chamber passes by the end of the pipe 257, the entire exhaust of fluid from the vane motor chamber 92 must pass through the needle valve 260 which is set to provide the desired body grinding feed for grinding a cylindrical portion of the work piece. The shuttle valve 315, in addition to serving as a means for providing a shoulder grinding feed when desired, also serves to cause a slightly rapid movement of the vane 88 which serves during the initial stages of the plunge-cut grinding cycle, in case no shoulder grinding feed is required, to take up the backlash between the feed screw 50 and the half nut 51.

By adjustment of the needle valve 321, the length of duration of the shoulder grinding feed may be readily regulated. By adjustment of the needle valve 319, the rate of the shoulder grinding feed may be readily adjusted as desired.

The selector valve 258 is shown in sectional view in Fig. 9, including the valve rotor 263 which is formed integral with a valve stem 330. A manual actuating knob 331 is fixedly mounted on the outer end of the valve stem 330 by means of which the valve rotor 263 may be readily adjusted. To facilitate positioning the selector valve 258, the valve stem 330 is provided with a pin 332 which projects in the path of a stud 333 carried by the

casing of the valve 258 and a stud 334 which is also fixedly mounted on the valve casing (Fig. 10). When the pin 332 is in the full line position as indicated in Fig. 10, the selector valve 258 is set for a plunge-cut grinding cycle, in which the grinding wheel 42 is fed directly into the work for a continuous stroke while the work piece 27 is rotated and held against axial movement. If it is desired to shift from a plunge-cut feed to a traverse grinding feed, the knob 331 and the valve stem 330 may be rotated in a clockwise direction so that the pin 332 is in position 332a (Figs. 2 and 10) in engagement with the stop pin 334 which shifts the valve rotor 45° in a clockwise direction from the sectional positions illustrated diagrammatically in Fig. 2. It will thus be readily apparent that by manipulation of the selector valve knob 331, the machine may be readily shifted from a plunge-cut grinding operation to a traverse grinding operation where an infeeding of the grinding wheel 42 is obtained only at the ends of the work table stroke.

To set the machine up for a traverse grinding operation, the valve rotor 263 is rotated in a clockwise direction so that the pipe 103 connects by means of a rotor chamber with a pipe 340 to convey fluid to and exhaust fluid from the start and stop valve 210. In this position of the valve rotor 263 of the selector valve 258a, the pipe 61 is disconnected from the pipe 104 and the pipe 104 is connected with the pipe 163 which is in turn connected with the start and stop valve 210. When it is desired to start a traverse grinding operation, the knob 209 is pulled out, that is, toward the left (Fig. 2), and fluid is allowed to exhaust from the valve chamber 101 of the control valve 95 and also from the valve chamber 322 of the shuttle valve 315. Simultaneously, the valve pistons 215 and 216 of the valve stem 211 allow fluid under pressure to flow through the pipe 163 into a chamber in valve rotor 263 of the selector valve 258d and into the pipe 104 which is connected to the control valve 95. Fluid enters the valve chamber 97 and shifts the valve stem 96 toward the right (Fig. 2) to facilitate feeding of the grinding wheel 42. No movement of the vane 88 is obtained until the shuttle valve 315 is also connected to the pipe 104. The fluid from the pipe 104 shifts the shuttle piston 316 and allows a predetermined amount of fluid to exhaust from the motor chamber 92 and thus move the vane 88 and thereby feed the grinding wheel 42 toward the work or only take up backlash as desired. In this position of the selector valve rotor 263 (258b), the passage 264 connects the pipe 257 with the pipe 265. Thus fluid will exhaust through the throttle valve 266 and through the shuttle valve 269 as previously described, thereby feeding the grinding wheel 42 a predetermined amount at the end of each stroke of the table 11.

When the valve rotor 263 of the selector valve 258c is shifted 45° in a clockwise direction, it disconnects the timer valve 300 and renders it inoperative and also connects the pipe 163 with the pipe 175 so that the actuation of the positions 170 and 235 is controlled by the valve stem 211 of the start and stop valve 210.

The operation of this improved grinding machine will be readily apparent from the foregoing disclosure. Assuming all of the valves to have been previously adjusted and set, when it is desired to start a grinding operation, the headstock switch 166 is closed to render the headstock electrical circuit operative, the grinding wheel driving motor 43 is started, and the fluid pump

200 is also started. As shown in Fig. 2, the valves are set for a plunge-cut grinding operation, a work piece 27 is placed in position on the work centers 28 and 29 and the table 11 is traversed longitudinally to position the desired portion of the work piece 27 in operative position opposite the grinding wheel 42. The lever 127 is then rocked in a clockwise direction (Fig. 1) to throw the feed gear 113 into position 113a in mesh with the gear 73 (Fig. 3). The knob 331 of the selector valve 258 is then positioned as shown in Figs. 9 and 10 to position the valve parts as shown in Fig. 2 in positions 258a, 258b and 258c so as to render the cycle time control valve 300 operative to control the duration of a plunge-cut grinding cycle. The knob 139 of the feed control valve 60 is then pulled out, that is, toward the left (Fig. 2) to initiate a plunge-cut grinding cycle. The shifting of the feed control valve 60 serves to start the rapid approach of the grinding wheel 42 and through the selector valve 258 starts the headstock driving motor 32, to open the valve 231 so as to start the flow of coolant fluid, and allow controlled exhaust of fluid from the vane motor 85 to produce the desired plunge-cut infeeding cycle.

The vane 88 of the vane motor 85 moves first at a comparatively rapid rate as controlled by the shuttle valve 315 to take up the backlash between the feed screw 50 and the half nut 51 before the grinding wheel 42 engage the work piece 27 to be ground. The movement of the vane 88 then slows down to a predetermined grinding feed as governed by the throttle or needle valve 260.

The plunge-cut feed continues for a predetermined time interval as controlled by the cycle timing valve 300. After the predetermined time interval, fluid is admitted to the chamber 281 of the feed control valve 60 to shift it toward the right into the position shown in Fig. 2 so that fluid under pressure will be admitted to the cylinder chamber 63 rapidly to move the grinding wheel 42 and its supporting slide 38 to a rearward or inoperative position.

If it is desired to set up the machine for a traverse grinding operation, the lever 127 is similarly thrown in a clockwise direction to engage the tumbler feed gear 113 with the gear 73. The knob 331 of the selector valve is rotated in a clockwise direction (Fig. 10) through approximately 45° to re-position the valve rotor 263 for a traverse grinding operation. This re-positioning of the selector valves 258 serves to render the vane type feed motor 85 operative to impart an intermittent infeeding movement of the grinding wheel 42 at the ends of the work table stroke. The knob 209 of the start and stop valve 210 is then pulled out, that is, toward the left (Fig. 2) which allows fluid under pressure to exhaust from one of the chambers of the table driving cylinder 15 to start a reciprocating movement of the table for a traverse grinding operation. Shifting of the start and stop valve 210 to this position also serves through the selector valve 258 to start the headstock motor 32 and to open the valve 231 to turn on the coolant fluid.

Through the selector valve 250, fluid is admitted to the valve chamber 97 to shift the valve stem toward the right, so that fluid under pressure is admitted to the motor chamber 91 to rapidly move the vane 88 in a counterclockwise direction rapidly to take up the backlash between the feed screw 50 and the half nut 51. The initial rapid movement of the vane 88 is governed by the shuttle valve 315 and the needle valve 321. After

this initial movement, the vane 88 is moved intermittently, during the reversal of the table at each end of its stroke, as governed by the shuttle valve 269 and the throttle valve 266.

5 The infeeding movement of the grinding wheel 42 at the ends of the table stroke is controlled in a manner above described by allowing a predetermined amount of fluid to exhaust from the vane motor 85 during each reversal of the movement 10 of the table 11. It will thus be seen that by adjustment of the control valves, either a plunge-cut grinding operation or a traverse grinding operation 15 may be readily obtained as desired.

15 After either a plunge cut or a traverse grinding operation has been completed, fluid under pressure is admitted to the cylinder chamber 63 to move the grinding wheel rearwardly to an inoperative position and is also admitted to the motor chamber 92 to return the motor vane 88 in a clockwise direction to its initial position.

20 It will thus be seen that there has been provided by this invention apparatus in which the various objects hereinabove set forth together with many thoroughly practical advantages are 25 successfully achieved. As many possible embodiments may be made of the above invention and as many changes might be made in the embodiment above set forth, it is to be understood that all matter hereinbefore set forth or shown in the 30 accompanying drawings is to be interpreted as illustrative and not in a limiting sense.

I claim:

1. A grinding machine having a base, a longitudinally reciprocable work supporting table, a 35 rotatable grinding wheel, a transversely movable slide therefor, means including a piston and cylinder to move said grinding wheel rapidly to and from a grinding position, means including a fluid motor to produce a grinding feed, control means 40 for said fluid motor to produce a continuous plunge-cut grinding feed of said wheel, control means for said fluid motor to produce an intermittent infeed of the grinding wheel during table reversal for a traverse grinding feed, and 45 a selector valve whereby either of said control means may be rendered operative while the other remains inoperative.

2. A grinding machine having a base, a longitudinally reciprocable work supporting table, a 50 rotatable grinding wheel, a transversely movable slide therefor, means including a nut and screw mechanism to feed said slide, means including a piston and cylinder to move said feed screw axially to impart a rapid movement of the grinding 55 wheel to and from a grinding position, means including a single vane-type fluid motor to rotate said screw to impart a relatively slow grinding feed to said slide, control means for said fluid motor to produce a continuous rotary movement 60 of said vane to impart a continuous plunge-cut feeding movement of said wheel, control means for said fluid motor to produce an intermittent rotary movement of said vane to impart an intermittent infeeding movement of the grinding 65 wheel during each table reversal for a traverse grinding operation, and a selector valve whereby said fluid motor vane may be actuated either continuously for a plunge-cut or intermittently for a traverse grinding operation.

70 3. In a grinding machine having a base, longitudinally reciprocable work supporting table, a rotatable grinding wheel, a transversely movable slide therefor, means including a piston and cylinder to reciprocate said table, a table actuated 75 reversing valve for said cylinder, means includ-

ing a nut and screw to feed said slide transversely, means including a fluid motor to rotate said screw so as to impart a feeding movement to said grinding wheel, a control valve for said motor, a needle valve to control the movement of said motor in one direction, a fluid actuated shuttle valve to control the exhaust of fluid through said needle valve, and means actuated by and in timed relation with said table reversing valve to actuate said shuttle valve during table reversal thereby to facilitate metering a predetermined volume of fluid through said needle valve to actuate the fluid motor and thereby impart a feeding movement to said grinding wheel.

4. In a grinding machine in accordance with claim 3, the combination with the parts and features therein specified, of a throttle valve to control the rate of movement of said shuttle valve so as to regulate the extent of said feeding movement at each reversal of said table.

5. A grinding machine having a base, longitudinally reciprocable work supporting table, a rotatable grinding wheel, a transversely movable slide therefor, means including a fluid motor to feed said slide to impart a grinding feed to said wheel, a manually operable control valve to initiate a grinding cycle, control means including a throttle valve to control the exhaust of fluid from one side of said fluid motor so as to control the rate of movement of said motor and thereby control the rate of the feeding movement of the grinding wheel, a fluid actuated shuttle valve arranged to allow a predetermined exhaust of fluid from said motor during the initial feeding movement to facilitate an initial rapid movement of the wheel slide to take up backlash between the parts of said feeding mechanism, a needle valve to control fluid exhausting from said shuttle valve to regulate the rate of said rapid movement of the slide, and a throttle valve to regulate the rate of movement of the shuttle valve so as to regulate the length of said initial rapid movement of the wheel slide.

6. A grinding machine having a base, a longitudinally reciprocable work supporting table, a rotatable grinding wheel, a transversely movable slide therefor, means including a nut and screw to move said slide transversely, means including a fluid motor to rotate said screw to impart a grinding feed to said wheel, a manually operable cycle control valve to initiate a grinding cycle, control means including a throttle valve to control the exhaust of fluid from one side of said motor so as to control the rate of rotation of said motor and said screw so as to control the rate of feeding movement of the grinding wheel, a fluid actuated shuttle valve arranged to allow a predetermined exhaust of fluid from said motor during the initial feeding movement to facilitate an initial rapid rotation of the feed screw to take up the backlash between the nut and screw before the grinding wheel engages a work piece, a needle valve to control fluid exhausting through said shuttle valve to regulate the rate of said rapid rotation of the feed screw, and a throttle valve to regulate the rate of movement of said shuttle valve so as to regulate the length of said initial rapid rotation of the feed screw.

7. A grinding machine having a base, a longitudinally reciprocable work supporting table, a rotatable grinding wheel, a transversely movable slide therefor, means including a nut and screw to move said slide transversely, means including a fluid motor to rotate said screw to impart a grinding feed to said wheel, a manually operable

control valve to initiate a grinding cycle, control means including a throttle valve to control the exhaust of fluid from one side of said fluid motor so as to control the rate of rotation of said motor and said screw to control the rate of the feeding movement of the grinding wheel, a fluid actuated shuttle valve arranged to allow a predetermined exhaust of fluid from said motor during the initial feeding movement to facilitate an initial rapid rotation of the feed screw to take up backlash between the nut and screw, a needle valve to control fluid exhausting through said shuttle valve so as to regulate the rate of said rapid rotation of the feed screw, a throttle valve to regulate the rate of movement of the shuttle valve so as to regulate the length of said initial rapid rotation of the feed screw, and means automatically to shift said control valve to a reverse position after a predetermined grinding operation to return said fluid motor to its initial position and also to return the grinding wheel to its initial or inoperative position.

8. A grinding machine having a base, a longitudinally reciprocable work supporting table, a rotatable grinding wheel, a transversely movable slide therefor, means including a nut and screw to move said slide transversely, means including a piston and cylinder to move said screw axially rapidly to position the slide and the grinding wheel, means including a fluid motor to rotate said screw to impart a grinding feed to said wheel, a manually operable control valve to admit fluid under pressure to said cylinder and said motor to initiate a grinding cycle, control means including a throttle valve to control the exhaust of fluid from one side of said motor so as to control the rate of movement of said motor and rotation of said screw so as to control the rate of feeding movement of the grinding wheel, a fluid actuated shuttle valve arranged to allow a predetermined exhaust of fluid from said motor during the initial feeding movement to facilitate a rapid rotation of the feed screw to take up backlash between the nut and screw, a needle valve to control fluid exhausting through said shuttle valve to regulate the rate of said rapid rotation of the feed screw, a throttle valve to regulate the rate of movement of said shuttle valve so as to regulate the duration of said initial rapid rotation of the feed screw, and means automatically to shift said control valve to a reverse position after a predetermined grinding operation to return said piston and said fluid motor to their initial positions and thereby move the grinding wheel and its supporting slide to an inoperative position.

9. A grinding machine having a base, a longitudinally reciprocable work supporting table, a rotatable grinding wheel, a transversely movable slide therefor, means including a nut and screw to move said slide transversely, means including a piston and cylinder to move said screw axially rapidly to position said slide and grinding wheel, means including a fluid motor to rotate said feed screw to impart a grinding feed to said wheel, control means therefor including a throttle valve to control the exhaust of fluid from one side of said motor so as to control the rate of said motor and the rotation of said screw to control the rate of feeding movement of the grinding wheel, a fluid actuated shuttle valve arranged to allow a predetermined exhaust of fluid from said motor during the initial feeding movement to facilitate a relatively rapid shoulder grinding feed, a needle valve to control fluid exhausting through said shuttle valve to regulate the rate of the shoulder

grinding feed, and a throttle valve to regulate the rate of movement of said shuttle valve so as to regulate the length of said shoulder grinding feed.

10. A grinding machine having a longitudinally reciprocable work supporting table, a rotatable grinding wheel, a transversely movable slide therefor, a nut and screw to feed said slide transversely, means including a piston and cylinder to impart a rapid axial movement to said feed screw to position the grinding wheel either in an operative or inoperative position, means including a fluid motor to impart a slow rotary movement to said feed screw, means including a manually operable control valve to admit fluid under pressure to said cylinder to move the grinding wheel to an operative position and thereafter to admit fluid under pressure to said fluid motor to initiate a grinding feed, and a time control valve to control the duration of said grinding feed, said time control valve being arranged after a predetermined movement to admit fluid under pressure automatically to shift said manually operable control valve and thereby terminate the grinding operation by reversing the flow of fluid under pressure to said cylinder and to said motor.

11. A grinding machine having a base, a longitudinally reciprocable work supporting table, a rotatable grinding wheel, a transversely movable slide therefor, a hydraulic feed motor which is arranged to feed said slide, means including control valves for said motor to impart either a continuous uniform feed to said slide for a plunge-

cut grinding operation or an intermittent feed to said slide at the ends of the table stroke for a traverse grinding operation, an electric motor to rotate a work drive motor, means including a switch to start the work drive motor, means including a piston and cylinder to actuate said switch to start said work drive motor, means including a source of coolant fluid, a control valve therefor, means including a piston and cylinder to open said coolant supply control valve, and a selector valve which is arranged in either a traverse grinding or a plunger-cut grinding position to start the work drive motor and turn on the coolant fluid when the grinding operation is started.
